UNITED STATES PATENT OFFICE

117,299

DESIGN FOR A COMBINED GROCERY REMINDER AND SPICE CABINET

Morton S. Thomas, Albion, Ind.

Application November 17, 1938, Serial No. 81,185

Term of patent 7 years

To all whom it may concern:

Be it known that I, Morton S. Thomas, a citizen of the United States, residing at Albion, in the county of Noble and State of Indiana, have invented a new, original, and ornamental Design for a Combined Grocery Reminder and Spice Cabinet, of which the following is a specification, reference being had to the accompanying drawing, forming part thereof.

I claim:

The ornamental design for a combined grocery reminder and spice cabinet, as shown.

MORTON S. THOMAS.
